C. R. SOULE.

Straw Carrier.

No. 10,461.

Patented Jan. 24, 1854.

UNITED STATES PATENT OFFICE.

CHARLES R. SOULE, OF FAIRFIELD, VERMONT.

THRESHER AND SEPARATOR OF GRAIN.

Specification of Letters Patent No. 10,461, dated January 24, 1854.

To all whom it may concern:

Be it known that I, CHARLES R. SOULE, of 5
Fairfield, in the county of Franklin and
State of Vermont, have invented certain
new and useful Improvements in the
Construction of Machinery for Threshing and
Cleaning Grain; and I do hereby declare
that the following is a full, clear, and exact
description thereof, reference being had
10 to the accompanying drawings, which form
a part thereof, in which—

Figure 1 is a vertical section through the
machine longitudinally. Fig. 2 is a side
elevation. Fig. 3 is a plan of the underside
15 of the guide board and shoe. Fig. 4, the
shoe, with its mode of suspension.

The nature of my invention consists in
the arrangement and construction of the
straw-carrier, the beaters connected
20 with, the shoe and its appendages, and the
movable board under the straw screen.

The advantages are, first, a reduction of
the length of the straw-carrier, together
25 with a perfect separation, a better mode
of vibrating the shoe, and a guard against
injury from getting a stone into the machine.

The construction of the parts is as follows: I form the frame of two posts (*a*, *a*)
30 on each side, which stand bracing at an
angle of about 45° , the bearing of the threshing
cylinder (*b*) being at their junction *a'*. On one side of the cylinder (*b*) is the feeding
trough (*c*), which terminates in a thin
35 piece of metal (*d*), that may be divided
into two or three divisions, more or less, if
need be. This thin strip of metal reaches
to the concave, and closes the space between
it and the other portion of the trough. The
concave and cylinder are of ordinary
40 construction, and the effect is, when a stone or
other hard substance that would be likely
to injure the machine gets into it, it is by
the cylinder thrown down with a force suffi-
cient to spring down the metal (*d*), and
45 escape below the concave without damage
to the operation of the machine. The parts
beyond the concave are for carrying off
the straw, and cleaning and separating the
grain. The first operation is to remove the
50 straw; and for this purpose a stationary
trough (*e*) extends from the thresher upward,
at an inclination of ten to fifteen degrees,
more or less. The sides of this trough
(*e*) are close, the bottom is composed of

55 slats, like a Venetian blind. Above this, and moving endways over it up and down, is a set of bars, (*f*), notched on their upper edges, as clearly shown in section, Fig. 1. They are connected with a cross head (*f'*), which slides on guide rods (*g*), fixed in 60 the sides of the frame. As these bars slide back toward the thresher the sides of the notches inclined to the plane of motion on the upper edges of the bars slip under the straw without carrying it back, while on returning the sides of the notches perpendicular to said plane of motion catch the straw and push it forward. Two pitmen (*h*), one on each side of the frame, connect it with 65 cranks on the axis of a beater (*i*), that is 70 located just above said bars (*f*); and, in its revolutions, beats out the grain as the straw passes forward from the threshing cylinder. This beater is covered with a cap which extends down, covering the trough to 75 the cylinder, and up for some distance beyond, terminating in a valve (*k*), which falls down upon the straw, and prevents any grain from flying out of the machine from the cylinder in that direction. Below the 80 stationary slats (*e*) there is a bottom board at (*m*), having a vibrating motion, the same as the bars (*f*), above named; the outer end of this board is suspended by straps (*n*), and the inner end is supported upon a 85 cross lever (*o*), below it. This lever (*o*) has its fulcrum in the frame at (*o'*) on one side, and extends across through the other stationary side of the machine, where it connects with an upright lever of the sec- 90 ond order, having its fulcrum at (*p*), the lever (*o*) being connected with it at its center; and its upper end connected by a pitman (*p'*) with the cross head of the bars (*f*), above named. The lever (*o*) is 95 jointed to the board (*m*), at its center. The shoe (*g*) is suspended by straps to the machine in the ordinary place, but so that both ends can be moved equally. It receives the 100 grain from the vibrating board (*m*), which by its vibrations insures the descent of the grain to the shoe, keeping all the parts clear. Besides the suspending straps, the shoe is 105 guided and controlled in its motion by two horizontal rods (*r*), one end of each of which are jointed to the side of the shoe, the other to the side of the machine. An arm at right angles to and forming a part of

the lever (*o*) is jointed to the shoe, as clearly shown in Fig. 1, and causes its sideway vibration. The screens, rake, &c., are like those of ordinary shoes; and the fan (*s*) for blast is located in the usual place, below the thresher. The bars (*f*) described above in the straw carrier are to be about three inches apart in the machine, extending up to the valve (*k*), beyond which every other one of said bars projects nearly or quite to the tip of the slats. This causes the straw to move faster till it gets beyond the valve, than it does afterward by which the straw gathers up and the grain is more entirely separated.

Having thus fully described my improved threshing machine, what I claim therein as

new, and for which I desire to secure Letters Patent, is—

1. The spring at the end of the feed board, 20 to prevent damage from stones getting into the machine.

2. The straw carrier and separator, consisting of the notched bars, having an end-way motion, and the beater *i*, as above specified, combined with the movable conducting board (*m*) for insuring the descent of the grain. 25

3. I also claim the mode of hanging and moving the shoe, as above described.

CHARLES R. SOULE.
